(57) **CLAIM**

The ornamental design for a grill pan, as is shown and described.

DESCRIPTION

FIG. 1 is a perspective view thereof of a grill pan, showing the new design;

FIG. 2 is a top elevational view thereof;

FIG. 3 is a right side elevational view thereof;

FIG. 4 is a left side elevational view thereof;

FIG. 5 is a rear elevational view thereof;

FIG. 6 is a front elevational view thereof; and,

FIG. 7 is a bottom elevational view thereof.

The broken line shown in the drawings depict portions of the grill pan that form no part of the claimed design.

1 Claim, 7 Drawing Sheets
